TRANSFORMER FOR ENERGIZING NEON SIGNS OR SIMILAR ARTICLE

Joseph E. Budovec, Hollywood, Ill., assignor to Jefferson Electric Company, Bellwood, Ill., a corporation of Delaware

Filed Mar. 11, 1960, Ser. No. 59,699

Term of patent 14 years

(Cl. D26—15)

FIG. 1

FIG. 2

FIG. 3

Fig. 1 is a front side elevational view of a transformer for energizing neon signs or similar article embodying my new design;

Fig. 2 is a top plan view thereof; and

Fig. 3 is a left end view thereof.

The rear side elevation is substantially identical to the front side elevational view of Fig. 1 and the right end elevation is substantially identical to the left end elevational view of Fig. 3, and the bottom is free of ornamentation.

I claim:

The ornamental design for a transformer for energizing neon signs or similar article, as shown and described.
